United States Patent Office

Des. 221,219
Patented July 20, 1971

221,219

SOFA

Thomas Winrow, 530 S. Sleight St.,
Naperville, Ill. 60540

Filed Nov. 30, 1970, Ser. No. 26,219

Term of patent 14 years

Int. Cl. D6—02

U.S. Cl. D15—11

The figure is a perspective view of a sofa illustrating my new design.

The back of the sofa is conventionally plain while the side not shown is substantially identical to the side shown.

I claim:

The ornamental design for a sofa, substantially as shown and described.
